JAMES KEMNAL, OF CHISLEHURST, AND JOHN HENRY, OF LONDON, ENGLAND,
ASSIGNORS TO THE BABCOCK & WILCOX COMPANY, OF BAYONNE, NEW JER-
SEY, A CORPORATION OF NEW JERSEY.

SOOT-BLOWING DEVICE.

1,377,622.

Specification of Letters Patent. Patented May 10, 1921.

Application filed December 15, 1920. Serial No. 430,989.

To all whom it may concern:

Be it known that we, JAMES KEMNAL and JOHN HENRY, subjects of the King of Great Britain, residing at Kemnal Manor, Kemnal Road, Chislehurst, in the county of Kent, England, and 112 Dalmeny avenue, Norbury, London, S. W., England, respectively, have invented certain new and useful Improvements in a Soot-Blowing Device, of which the following is a specification.

Our invention relates to soot-blown devices for cleaning the soot from the tubes of water tube boilers. It has been proposed previously, in such cleaners, to arrange the soot-blowing elements, or distributing pipes, transversely of the longitudinal axes of the tubes either above or below the same and to furnish the blower units with nozzles adapted to be rotated, the discharging opening 15 of said nozzles being disposed obliquely to the axis of the blower unit to discharge throughout the length of the spaces between the tubes.

One of the objects of our invention is to provide an improved valve arrangement for controlling the supply of the cleaning medium to the blower units. Another object is to provide an improved construction of soot-blowing element particularly suited to such improved controlling means. A further object is to provide improved means permitting the blower elements to move freely in any direction and independently of the boiler side walls, whether the latter 30 be of brickwork or of iron casings. With these and other objects in view, our invention consists in the arrangements and constructions hereinafter described and more particularly pointed out in the appended 35 claims.

The invention is illustrated in the accompanying drawings, in which Figure 1 is a longitudinal section of one of the improved distributing or blower elements; Fig. 2 is a section on the line 2-2 of Fig. 1, showing a part of the construction; Fig. 3 is a section on the line 3-3 of Fig. 4; Fig. 4 is a section on an enlarged scale on the line 4-4 of Fig. 1; Fig. 5 is a detail view of one of the nozzles; Fig. 6 is an end view of a blower device, showing the supply connections for the cleaning fluid and the controlling indicator; Fig. 7 shows an arrangement of a series of the improved blower de-

vices applied to a Babcock & Wilcox type 55 of boiler; Fig. 8 is a transverse section of the boiler illustrated in Fig. 7, showing one of the blower units in operation; Fig. 9 is a sectional elevation on the line 2-2 of Fig. 1, showing the manner in which the 60 blower unit is suspended to allow for expansion, and Fig. 10 is a detail view illustrating one of the brackets by which the blower element is secured to boiler tubes.

Referring to the drawings, A denotes the 65 soot-blowing element to which fluid under pressure, such as compressed air or steam, is supplied. The soot-blowing elements may conveniently be secured to the top row of tubes of the boiler by brackets B, each of 70 the elements preferably being provided with two independent chambers, compartments or passages A¹ and A² formed by a partition 10.

Each of the chambers or passages A¹ and A² is fitted with a plurality of nozzles A³, 75 the nozzles for the separate passages pointing in different directions and each nozzle being preferably provided with a number of differently directed jet orifices A⁴ and A⁵, as shown in Fig. 5, for a purpose explained later.

From an inspection of Fig. 8, it will be apparent that oblique aisles are formed inclined in two directions, one such set of oblique aisles being indicated by the lines 85 from the series of nozzles shown in that figure as being directed toward such aisles. Similarly, the series of nozzles at the top of the blower element are arranged so that, when the element is turned through a half- 90 turn, this series of nozzles will coöperate with the other set of aisles inclined to the set indicated by the straight lines of Fig. 8.

To each distributing pipe or soot-blowing element A is connected, by means of flanges 95 or other suitable connections, a valve body C formed with two internal ports C¹ and C² cast or machined therein, which ports register with passages A¹ and A² in such blower element formed by the partition 10.

Cast in one with the valve body C or otherwise secured thereto, is a hand wheel or chain wheel C³, which can be operated from the ground if necessary by the usual light chain C⁵.

Within the valve body C is mounted a valve member D in which is formed an internal central passage having an elongated

port D^1 , preferably arcuate in cross-section, as indicated in Fig. 2, so as to overlap considerably the ports A^1 , A^2 when in registry with either, the valve D being kept tight by 5 the usual packing gland E . The supply piping is connected to each blower unit by a bent pipe F , as best shown in Figs. 1 and 6.

The valve body C , as shown in Figs. 1 10 and 9, is supported from a spring-balance neck or sleeve piece G , supported by means of a bolt H , or the like, from a lug on a box K secured to the side wall of the casing of the boiler, a spring G^1 being interposed between the nut on the bolt and the box K . This spring-balanced neck or sleeve G permits the blower element to slide or move in any direction when any expansion of the latter takes place or should the brickwork 15 in the side wall move in the setting, and at the same time maintains a seal between the valve body C and the box K . As will be seen from Fig. 1, a portion of the outer surface of the valve body C is made spherical, 20 as at C^6 , to facilitate its movement within the sleeve piece G . The sleeve piece G is preferably guided to some extent in its movement relatively to the box K by providing the box with projecting studs K^2 25 (see Fig. 9) entering oval or other recesses in the adjacent faces of the sleeve piece. 30

The box is also provided with a stop K^1 for coöperation with a stop C^4 on the back of the hand or chain wheel C^3 .

35 The blower element may be made in one or more connected pieces, according to the width and size of boiler, and each passage at the end remote from the operating end may be fitted with plugs to permit the passage to be cleared of any impediment.

When cleaning the soot from the boiler tubes with steam as the cleaning medium, a drain pipe L with valve M is required, as shown in Fig. 7. When compressed air is 45 used as the cleaning medium, the drain pipe and valve are not required.

As the valve D is stationary, port D^1 will always be at the bottom side, and when the indicator 11 on the hand or chain wheel C^3 50 is vertical, corresponding to the shut or closed position, in the form illustrated, as shown in Fig. 6, the ports C^1 and C^2 in the valve body C , along with chambers A^1 and A^2 of the blower unit A , will be closed, as 55 shown in Fig. 9.

The operation of the apparatus is as follows:

By revolving the hand or chain wheel to the left-hand side, port C^1 and chamber A^1 60 are brought into communication with port D^1 , bringing the jets of chamber A^1 in contact with the space between the tubes slanting to the left-hand side, as indicated by lines in Fig. 8. Now, as soon as contact is 65 made between ports D^1 and C^1 , the cleaning

medium rushes out of the jet holes of the nozzles A^3 of chamber A^1 only, passing into the spaces between the tubes to the left-hand side. This continues until the stop C^4 on the hand or chain wheel C^3 is stopped by 70 the stop K^1 on the bottom flange of the box K . The wheel is reversed and the same operation is repeated until the indicator is again vertical. This completes the cleansing of the inclined spaces between the tubes to 75 the left-hand side.

Now the wheel is revolved to the right-hand side, and this brings port C^2 and chamber A^2 into register with port D^1 , the port C^1 and chamber A^1 being closed, and 80 while the wheel is being revolved, the cleaning medium rushes through the nozzles A^3 of the chamber A^2 and cleans the spaces between the tubes which incline to the right-hand side. As the wheel revolves, the cleaning medium continues to flow through the nozzles A^3 until the stop C^4 on the wheel again abuts against the stop K^1 on the box K . As the wheel cannot turn further and the cleaning medium is still rushing out 90 of the nozzles into the spaces between the tubes which incline to the right-hand side, the wheel must be reversed and revolved until the indicator is brought into the upright position, when the ports C^2 and chamber A^2 are closed to the valve port. This 95 completes the operation for the first blower unit, and the operation is repeated with all the other blower units until the cleaning of the boiler tubes is completed. 100

Now, as the planes of the spaces between the tubes lie at an angle to the blower units, and when the latter is being revolved the cleaning medium which passes from the jets travels through an arc of a circle, in certain 105 positions some of the cleaning medium from the jet orifices in the nozzles moves away from the center line of the spaces. To overcome this disadvantage we provide a number of jet orifices A in each nozzle, as shown in Fig. 5, the outer holes being machined to different angles from the center hole, the center hole being set central at the required angle to suit the inclination of the spaces between the tubes. This arrangement insures that the whole of the spaces between the tubes, both in depth and length, are 115 scoured by the cleaning medium.

It will be clear that the valve arrangement may be employed with an undivided blower unit having the nozzles all located on the same side of the distributing pipe. 120

We claim:

1. A soot-blowing device comprising a soot-blowing element provided with separate 125 passages and series of nozzles arranged obliquely to the axis of said element and communicating with the respective passages, one series of nozzles being arranged to direct a cleaning fluid through one set of 130

oblique aisles in a group of boiler tubes and another set being arranged to direct a cleaning fluid through another set of oblique aisles, and means for connecting said 5 passages alternately with a source of fluid supply.

2. A soot-blowing device comprising an element having separate passages and a series of obliquely-arranged nozzles on opposite sides of the element and communicating with the respective passages, one of such series being arranged to direct a cleaning fluid through one set of oblique aisles in a group of boiler tubes and the other 10 series being arranged to direct the fluid through another set of oblique aisles, and means to connect said passages alternately with a source of fluid supply.

3. A soot-blowing device comprising an 20 element having separate passages and a series of obliquely-arranged nozzles on opposite sides of the element and communicating with the respective passages, one of such series being arranged to direct a cleaning fluid through one set of oblique aisles in a group of boiler tubes and the other series being arranged to direct the fluid through another set of oblique aisles, means whereby said tube may be rotated to bring 30 each of said series into position to direct jets of the fluid through the aisles with which the series coöperates, and means to connect each passage with a source of supply only when the series is in position to act 35 on the aisles with which it coöperates.

4. A soot-blowing device comprising an element having separate passages and two series of obliquely-arranged nozzles, communicating with the respective passages, one 40 of such series being arranged to direct a cleaning fluid through one set of oblique aisles in a group of boiler tubes and the other series being arranged to direct the fluid through another set of oblique aisles, means whereby said element may be rotated to bring each of said passages into position to direct jets of a cleaning fluid through the 45 aisles with which the series coöperates, and means to connect each passage with a source of fluid supply while the associated series is being rotated in alinement with the aisles with which it coöperates.

5. A soot-blowing device comprising an element having separate passages and two 55 series of obliquely-arranged nozzles communicating with the respective passages, one of such series being arranged to direct a cleaning fluid through one set of oblique aisles in a group of boiler tubes and the other series being arranged to direct the fluid through another set of oblique aisles, means whereby said element may be rotated to bring each of said series into position to direct jets of a cleaning fluid through the 60 aisles with which the series coöperates, and

means to connect each passage with a source of fluid supply while the associated series is being rotated in alinement with the aisles with which it coöperates, each nozzle having a plurality of openings whereby the fluid 70 is directed into the aisles as the nozzles are rotated.

6. A soot-blowing device comprising a rotary soot-blowing element provided with a plurality of nozzles and formed with separate 75 passages with which different nozzles communicate, a source of fluid supply, and means for connecting said passages alternately to said source of fluid supply.

7. In a soot-blowing device, a stationary 80 valve member provided with a port adapted to be connected to a supply of fluid under pressure, and a rotary soot-blowing element provided with separate passages and a separate series of nozzles communicating with 85 the respective passages, the end of the element forming a rotary valve member provided with ports communicating with said passages and adapted to communicate with and to be cut off from said stationary port 90 by rotating said member.

8. In a soot-blowing device, a stationary valve member provided with a port adapted to be connected to a supply of fluid under pressure, and a rotary soot-blowing element 95 provided with separate passages and a separate series of nozzles communicating with the respective passages, the end of the element forming a rotary valve member provided with ports communicating with said 100 passages and adapted to communicate with and to be cut off from said stationary port by rotating said member, one series of nozzles being arranged to direct the cleaning fluid through one set of oblique aisles 105 in a group of boiler tubes and the other series being arranged to direct the fluid through another set of oblique aisles.

9. A soot-blowing device comprising a soot-blowing tube, a wall having a clearance 110 opening through which the tube projects, a member surrounding the tube adapted to seal said opening, and means for resiliently supporting said member from said wall.

10. A soot-blowing device comprising a soot blowing tube, a wall having a clearance opening through which the tube projects, a member surrounding the tube and slidably closing said opening and arranged to permit the tube to be tilted and to be moved 120 bodily at right-angles to its axis and constructed and arranged to prevent the escape of gases between the tube and said member and through said clearance space, regardless of the position of the tube.

11. A soot-blowing device comprising a soot-blowing element comprising a tube extending across and attached to the boiler tubes, a support for the end of the blower element fixed in the wall of the setting, and 130

resilient connections between the support and the end of the tube.

12. A soot-blowing device comprising a soot-blowing element extending across and attached to the boiler tubes, a support for the end of the blower element fixed in the wall of the setting, and resilient connections between the support and the end of the tube constructed and arranged to permit relative movement between the blower element and the support in a plane parallel to the boiler tubes.

13. A soot-blowing device comprising a soot-blowing element, a sleeve inclosing said element, means for resiliently supporting said sleeve from a stationary part, said element being provided with a spherical portion engaging said sleeve.

14. A soot-blowing device comprising a soot-blowing element, a sleeve inclosing said element, means for resiliently supporting said sleeve from a stationary part, said element being provided with a spherical portion engaging said sleeve, said sleeve forming a seal between said element and said stationary part. 20 25
